ABRASIVE EQUIPMENT

Verne E. Minich and Gerald N. Grove, Mishawaka, Ind., assignors to The American Foundry Equipment Company, Mishawaka, Ind., a corporation of Delaware

Application December 30, 1933, Serial No. 704,777

13 Claims.

(Cl. 51—9)

This invention relates to abrasive equipment and more particularly to certain improvements in the method and apparatus for cleaning metal sheets, castings and the like disclosed in the application of Verne E. Minich, Serial No. 692,743, filed October 9, 1933.

This invention is concerned with the provision of improved means for feeding abrasive into the path of the moving blades. The machine comprises generally a rotor including a disc which may be removably mounted on a rotatably mounted drive shaft. A drum member is centrally mounted on one side of the disc. The blades project from the drum side of the disc and are arranged in uniform spaced relationship. The inner ends of the blades are spaced from the drum member so as to provide a free end open passage between the periphery of the drum and the inner ends of the blades.

The abrasive is fed on to the outer periphery of the drum by means of a feed pipe which is adjustable in position to deposit the abrasive on the drum periphery at the desired point. The drum periphery may be covered or carpeted with a blanket of wear resisting rubber which operates to retain the abrasive on the drum periphery until centrifugally thrown therefrom. As a modified arrangement the drum periphery may be provided with a plurality of transversely extending ribs which may be arranged in radially staggered relationship to the throwing blades of the machine. The ribs or corrugations operate to collect the abrasive fed on to the drum periphery as individual charges which are thrown from the rotating drum into the path of the moving blades. By means of this arrangement more complete directional control of the thrown abrasive, as well as a more uniform distribution of the abrasive over the surface operated upon, is accomplished. Each blade picks up a regulated amount of the abrasive charge thrown in front of it. The blade operates to change the direction of the movement of the abrasive particles into approximately the direction of the moving blades. Substantially simultaneously the blade operates to bat, hurl or throw the abrasive at blasting velocity in a predetermined direction. The discharge end of the feed pipe is so constructed as to distribute the abrasive uniformly over the peripheral width of the drum. The blades are made of wear resisting metal and are preferably of considerable thickness to resist wear.

An object of this invention is to provide an improved abrasive machine so constructed as to

throw the abrasive at an abrading velocity against the work operated upon under full directional control and distribute the abrasive uniformly over the surface being treated.

Another object of this invention is to provide improved means for feeding the abrasive into the path of the moving blades in the most effective and efficient manner.

Another object of this invention is to provide an improved abrasive throwing machine which comprises few moving parts, which is simple and strong in construction, which can be economically made and assembled, which has a low power consumption for the work done, which imparts to the abrasive a highly abrasive velocity, which operates in such a manner as to reduce the wear of the abrasive particles on the various parts of the machine, which occupies a small space area, which effects uniform distribution of the abrasive over the work, and which is highly adaptable for the cleaning of metal sheets, castings, forgings, metal parts and other articles.

Other objects of this invention will become apparent as the disclosure proceeds.

In order that a clearer understanding of our invention may be had, attention is hereby directed to the accompanying drawings, forming part of this application and illustrating certain possible embodiments of our invention.

Referring to the drawings:

Fig. 1 is a face view of the abrasive machine with the abrasive particles being shown fed into the machine and thrown therefrom, certain parts being broken away to more clearly illustrate the construction;

Fig. 2 is a vertical cross sectional view through the machine, this view being taken on line 2—2 of Fig. 1;

Fig. 3 is a face view of an abrasive machine of somewhat modified construction;

Fig. 4 is a vertical cross sectional view through the machine shown in Fig. 3, this view being taken on line 4—4 of Fig. 3; and

Fig. 5 is a diagrammatic view illustrating the operation of the machine shown in Figs. 3 and 4 and particularly the action of the blades when operating upon successive charges of the abrasive thrown in the path thereof.

Similar reference characters refer to similar parts throughout the several views of the drawings and specification.

An abrasive machine, as shown in Figs. 1 and 2, comprises generally a disc member 1 of wear resisting metal and of generally circular shape removably mounted on a rotatable drive shaft 5.

The hub 6 fixed to the disc by means of removable bolts 7 connects the drive shaft to the disc 1. A drum member comprising a cylindrical side wall portion 2 is centrally mounted on the disc. The drum side wall may be cast as an integral part of the disc member 1 if desired. A plurality of blades are radially arranged in uniform spaced relationship around the periphery of the disc member 1. The blade 3 may be cast integral with the disc 1 or they may be detachably secured thereto as found convenient and desirable. The blades are preferably made of hard wear resisting metal and are of considerable thickness to give long wear. The radial length of the blades 15 and the drum diameter may both be varied as circumstances may require. A path for the moving abrasive, however, is preferably provided between the inner end of the blades and the drum periphery. A ring member 23 joins the blades 3 and gives rigidity to the assembly. The ring member 23 may be cast integral with the blade 3 and the disc 1 or it may be bolted or otherwise secured thereto.

The open side of the rotor is closed by means 25 of a stationary disc 8 supported by bolt 15 extending through the upstanding flange of a frame member 9 supported by a suitable frame 11.

An elongated opening 17 is cut through the 30 stationary disc 8 to receive the discharge end 13 of the feed pipe 12 through which the abrasive is fed on to the drum periphery 2. The feed pipe 12 is adjustably supported by means of a bracket 14, one end of which is secured to the feed pipe 12 and the other end adjustably secured to the screw 15 by means of the nut 16, as clearly shown in Figs. 1 and 2. The feed pipe 12 and the closure disc 8 are held stationary during the operation of the machine but both may be adjusted 40 so as to position the discharge end 13 of the feed pipe 12 at any desired location with respect to the drum periphery 2 and the moving blades 3. The direction of discharge of the abrasive from the rotor can thus be varied as desired.

45 The discharge end 13 of the feed pipe 12 is shaped to provide an elongated nozzle opening which will distribute the abrasive uniformly over the full width of the side wall 2 of the drum. The side wall 2 may be covered by a rubber blanket 21 or other material which will frictionally retain to a limited extent the abrasive particles deposited thereon. The blanket 21 is preferably vulcanized to the drum periphery 2 and is further held in position by an outwardly flared lip 55 20 extending from the drum side wall 2.

A regulated supply of abrasive is fed from the discharge end 13 of the feed pipe 12 on to the friction surface 21 of the drum. The abrasive is retained on the rubber surface 21 and is carried along by the rotating drum until tangentially thrown therefrom at a speed which is approximately that of the drum periphery. The abrasive, tangentially thrown from the rotating drum, shoots outwardly into the path of the moving blades as illustrated in Fig. 1. Particles are caught by the moving blades 3 advancing at a great speed. The direction of the moving particles when contacted by the blade is then changed to substantially the direction of the 70 moving blade. As the blade is moved further the velocity of the particles is further increased as the particles deposited thereon are batted, hurled or thrown centrifugally from the rotating blade in a predetermined direction.

75 The abrasive particles *a* are variously dis-

tributed by the moving blades over an arc which approximates one-quarter of the drum circumference and are uniformly distributed over the work W along a path approximately two and one-half feet in length. The abrasive particles are given little incentive to slide along the surface of the blade since the particles are given an impelling force which is substantially at right angles to the moving blades. The abrasive is thus given little opportunity to wear the blades. 10

There is shown in Figs. 3 and 4 a blasting machine of somewhat modified construction. The main structural difference resides in the provision of ribs or corrugations 33 positioned at spaced intervals across the side wall 2 of the 15 drum. The blades 3 radially arranged around the disc member 2 are spaced from the side wall 2 of the drum so as to provide a clear passage therebetween. The blades as shown may be generally V-shaped with the rear side wall 35 of 20 one blade and the throwing side wall 34 of the following blade forming a slightly contracted discharge outlet through which the abrasive is thrown and distributed. A ring member 23 extends around the radially spaced blades and may 25 be cast integral therewith or secured thereto by means of machine screws 30.

The abrasive is fed on to the periphery of the rotating drum 2 through the feed pipe 12. The abrasive is distributed uniformly over the entire 30 width of the drum through an elongated discharge opening in the discharge end 13 of the feed pipe. The abrasive *a* discharged upon the periphery of the drum 2 gathers or drifts against the advancing side of the ribs 33 and is thrown as separate charges into the path of the moving blades 3. Satisfactory results have been obtained by providing a rib 33 on the drum for each blade spaced peripherally about the drum. The ribs 33 are also preferably arranged in staggered 35 relationship with respect to the blades 3 as illustrated more particularly in Figs. 3 and 5, so that the abrasive charge will be thrown between the blades before it is struck by the following blade. The abrasive thrown from the respective ribs 40 travels at less velocity than the moving blades. Consequently, the abrasive is struck by a blade which follows the rib from which it is thrown. As illustrated more particularly in Fig. 5, it is believed that the abrasive charge *a* thrown forwardly by the rib R is struck by the following blade A at the point A' and the abrasive thrown from the rib S is struck by the blade B when it arrives at the point B'. The wheel travels at approximately 2250 revolutions per minute and 45 the abrasive *a* is thus impinged upon the work W with abrasive velocity uniformly over a path which is approximately twice the diameter of the rotor. For example, a rotor having a diameter of nineteen and one-half inches moving at a 50 speed of 2250 revolutions per minute would effectively clean a path approximately two and one-half to three and one-half feet in length with the work advancing from under the wheel from six to ten feet per minute. The abrasive 55 thrown from the rotating drum in charges is thrown and dispersed by the blades so as to clean the work evenly and uniformly over the area acted upon. The abrasive is caught by the ribs 33 and is thus prevented from slipping or sliding 60 along the periphery of the rotating drum. Consequently, the abrasive *a* is thrown from the drum at a speed which approaches the speed of the rotating drum thus obtaining a maximum speed efficiency. When the moving blades 3 65

contact the abrasive the speed which it has attained by reason of the action of the moving ribs 33 is further augmented and increased without any appreciable loss of speed by reason of interference from the blades or other parts of the machine.

The open side of the drum may be closed by a disc 32 which may be cast integral with the drum 2 or bolted thereto by means of the through bolts 10. The space between the outer edge of the closure disc 32 and the inner edge of the ring 23 provides ample space for insertion of the discharge end 13 of the feed pipe 12.

The machine above described possesses a high degree of efficiency. The velocity given the abrasive by the throwing action exerted by the rotating drum is not slowed up or impaired by any interference due to the blade action. The blades 3 pick up the flying abrasive and augment or increase its velocity to substantially the velocity of the rotating blades. When the machine is rotated at approximately 2250 revolutions per minute, the abrasive is given a velocity sufficient to efficiently and effectively scour 25 forgings and castings of the hardest material.

The direction in which the abrasive is thrown may be regulated by the discharge end 13 of the feed pipe with respect to the moving drum and blades. The abrasive is discharged from approximately one-fourth of the wheel circumference under normal operating conditions of 30 2250 revolutions per minute. The area of discharge, however, will depend upon the rotating speed of the machine, the length of the blades, the 35 position of the discharge outlet, the drum diameter and the position of the machine with respect to the work.

The position of the ribs 33 with respect to the blades 3 of the machine shown in Figs. 3 and 4 40 may be varied as found desirable. The ribs 33, therefore, are preferably removably mounted upon the drum so as to permit this adjustment. The same object may be accomplished by providing a drum 2 which is adjustably mounted 45 upon the disc 1 so that the ribs 33 are automatically adjusted in the desired position with respect to the blades 3 by adjusting the position of the drum 2 with respect to the disc 1.

The form of the invention illustrated in 50 Figures 3, 4, and 5 of the drawings is claimed in our divisional application, Serial No. 271,992, filed May 5, 1939.

The machine above described is adapted for a variety of different uses such as for the cleaning 55 of metal sheets and other articles. The machine may be mounted on any suitable apparatus. The machine is made of few parts, and may be inexpensively manufactured and assembled. It is furthermore, strong and durable in construction, 60 safe and substantially foolproof in operation, requires little floor space, and is highly efficient.

While certain novel features of the invention have been disclosed and are pointed out in the annexed claims, it will be understood that various 65 omissions, substitutions and changes may be made by those skilled in the art without departing from the spirit of the invention.

What is claimed is:

1. An airless abrasive machine for throwing 70 abrasive particles at a blasting velocity comprising a rotatable drum, means for depositing abrasive on the outer periphery of said drum, and means spaced from and arranged around said drum for increasing the speed of the abrasive thrown by the rotating drum, said depositing

means being so arranged that the abrasive moves but once across the path of said speed increasing means.

2. An abrasive machine including in combination, a rotatable drum, means for depositing 5 abrasive on the outer periphery of said drum, and a plurality of radially extending blades spaced from said drum and operative to throw the abrasive in a predetermined direction as it is centrifugally thrown from the drum. 10

3. An abrasive blast machine including in combination, a rotatably mounted member, a drum fixed to said member, blades spaced from said drum and peripherally positioned around said member, and means for depositing abrasive 15 on the outer periphery of said drum.

4. An abrasive machine including in combination, a rotatably mounted disc, a drum centrally mounted on one side of said disc, blades carried by said disc and radially arranged around but 20 independent of said drum, said blades having a radial length which is a fraction of the disc radius, and off-center means adjacent the inner end of said blades for depositing abrasive on 25 said drum.

5. An abrasive machine including in combination, a rotatable shaft, a disc removably mounted on the end of said shaft, a plurality of throwing blades radially arranged and laterally projecting from one side of said disc, a drum for feeding 30 abrasive outwardly across the inner ends of said blades and into the path of movement thereof, and a stationary disc enclosing said blades.

6. A rotor for throwing a blast of abrasive comprising a rotatably mounted disc, a drum fixed to 35 said disc, a plurality of blades radially arranged around said drum and laterally extending from said disc, said blades having a radial length which is less than the disc radius, a stationary disc for closing the open side of the rotor, and off-center 40 means adjacent the inner ends of said blades extending through said stationary disc for depositing abrasive on said drum.

7. An airless abrasive machine comprising a rotatable shaft, a disc removably mounted on the 45 end of said shaft, a drum centrally mounted on said disc, a plurality of throwing blades radially arranged and laterally projecting from one side of said disc, said blades extending from the outer periphery of said disc radially inwardly a fractional 50 distance of the disc radius, and adjustable means adjacent the inner ends of said blades for depositing abrasive on said drum, said drum being operative to throw the abrasive tangentially therefrom and substantially radially across the 55 inner ends of said blades.

8. An airless abrasive machine comprising in combination, a rotatable shaft, a disc removably mounted on the end of said shaft, a drum fixed to and laterally extending from one side of said disc, a plurality of throwing blades spaced from the periphery of said drum radially arranged and laterally projecting from said disc, and adjustable means for depositing abrasive on said drum. 60

9. An abrasive machine comprising a rotatable 65 drum, means for depositing abrasive on the outer periphery thereof, means spaced from the drum for throwing the abrasive as it leaves the rotating drum, and a carpet covering on the outer periphery of said drum operative to hold the abrasive 70 on the rotating drum against sliding movement and until centrifugally thrown therefrom.

10. An abrasive machine comprising in combination, a rotatable shaft, a disc mounted on the end of said shaft, a drum fixed to and laterally 75

extending from one side of said disc, a plurality of throwing blades spaced from the periphery of said drum radially arranged and laterally projecting from said disc, and a reinforcing ring connecting the projecting ends of said blades.

11. An airless abrasive machine comprising a rotatable drum, a feed pipe, said pipe having a discharge outlet positioned adjacent to and extending into the machine and across substantially the full width of the drum periphery, and means for throwing the abrasive as it leaves the rotating drum, said discharge outlet being so arranged that the abrasive moves but once across the path of said throwing means.

15. 12. A machine for cleaning metal sheets, castings and the like which includes, rotatable throwing blades, a drum, means for depositing a stream of abrasive at a predetermined point on the outer periphery of said drum, means for rotating said drum at a speed sufficient to throw the abrasive

tangentially therefrom and thus give the charge an initial velocity, in the general direction of rotation of said blades, said blades being operative to bat and hurl the moving abrasive so as to increase the velocity thereof sufficient to exert 5 the desired abrasive action upon the material to be cleaned when impinged by the abrasive particles.

13. An abrasive machine comprising, a rotatable drum, means for uniformly distributing 10 abrasive on the outer periphery of said drum, a series of V-shaped blades radially arranged around said drum for throwing the abrasive as it leaves the rotating drum, each of said blades having the apex thereof directed inwardly so as 15 to provide a contracted abrasive discharge opening between adjacent blades.
